CASKET DISPLAY BIER

Max Litchfield, 3637 Silsby Road, Cleveland Heights,
Ohio, and Morris Lange, 3271 Warrensville Center
Road, Shaker Heights, Ohio

Filed Nov. 9, 1964, Ser. No. 82,519

Term of patent 14 years

(Cl. D19—9)

The single figure is a perspective view of a casket display bier, showing our new design, the opposite side and end not shown being substantially mirror images, respectively, of the side and end shown.

We claim:

The ornamental design for a casket display bier, as shown and described.
